Gardner D. Pearson

ATTORNEY.

UNITED STATES PATENT OFFICE.

ARTHUR CORNELLIER, OF DRACUT, MASSACHUSETTS.

BARBER'S COMB.

Application filed April 28, 1922. Serial No. 557,210.

To all whom it may concern:

Be it known that I, ARTHUR CORNELLIER, a citizen of the United States, residing at Dracut, in the county of Middlesex and 5 State of Massachusetts, have invented certain new and useful Improvements in Barbers' Combs, of which the following is a specification.

This invention relates to combs for use in 10 the human hair, and more particularly to combs such as are used by barbers in cutting hair.

I am aware that guides have been devised to determine the distance of a comb from 15 the head whereby the length of the cut can be regulated, but this device is for a different purpose.

In cutting hair by barbers, particularly where clippers, and still more particularly 20 where power clippers are used, it is customary for the barber to hold the clippers in one hand and the comb in the other, the clippers resting on and being guided by the comb.

25 Where a snarl or obstruction is encountered, the clippers frequently slip from their proper position on the comb and make what is known as a gash in the hair because they slip off the comb while still cutting.

30 This device is a comb having cutter guides which prevent such slipping.

In the drawings, Figure 1 shows in elevation an outline of a human head together with the hands of a barber, with a comb of 35 my construction used with hand clippers.

Fig. 2 is an elevation similar to Fig. 1 showing, however, power clippers.

Fig. 3 is an elevation of a comb of my construction having guides half the length 40 on one side and half the length on the other side.

Fig. 4 is a sectional elevation on either of the two lines 4—4 or 4—4 of Fig. 3.

Fig. 5 is an elevation of a comb which tapers from one end to the other, provided 45 with guides of my construction the full length on one side only.

Fig. 6 is a sectional elevation showing a modified form of guide which I prefer.

50 In the drawings, A represents a human head, B the hair thereon and C a comb of my construction.

F represents the left hand and G the right of the operator, while H represents hand

clippers having the handles 30 and 31 and a 55 cutting edge 32.

This cutting edge 32 is ordinarily straight as shown.

The comb includes a back 10 having substantially parallel teeth 11 running at substantially right angles therefrom, each tooth having a base 12 and a tip 13.

These teeth are so cut away that cutter guides 20, running in a line substantially parallel with but at a distance from the bases 12 of the teeth, project outwardly therefrom thereby forming guiding surfaces 21. These guiding surfaces preferably extend in a substantially parallel line with the bases of the teeth as described. 70

In operating the cutter, one corner of the cutting edge 32 may be pressed against the cutter guides 20 and moved along as shown in Fig. 1. These cutter guides prevent the clippers from slipping and making a gash. 75

In Fig. 2, the power cutters R of any common type are shown, being propelled by a flexible shaft such as 40. These have a cutting edge shown at 42 which ordinarily is substantially straight. 80

In Fig. 2, the cutting edge 42 is shown as pressed along its length firmly against the line of cutter guides 20. It is obvious that whether the whole length or one corner only is pressed against the cutter guides, it prevents the clippers from slipping. 85

As shown in Figs. 3 and 4, the cutter guides may extend halfway on one side and halfway on the other of a comb such as C. In Fig. 5, the comb T tapers from the end 48 to the end 49 the bases of the teeth running along the line 50 while the tips of the teeth are represented by line 52 and the line of cutter guides by 51. 90

In Fig. 6, the cutter guides represented by 21 have an overhang 23 which helps to keep the cutting edge of the clippers down so that it will not run over the tops of the guides. 95

I claim:

1. The combination in a comb having a straight back and substantially parallel teeth running at substantially right angles therefrom, of a series of cutter guides each projecting from a tooth and having a guiding surface between its base and its tip, said guiding surfaces each having an overhanging top and facing towards and running in 100 105

a straight line substantially parallel with but at a distance from the bases of the teeth.

2. The combination in a comb having a straight back and substantially parallel teeth running at substantially right angles thereto, of a series of cutter guides each

projecting from a tooth and having a guid-

ing surface between its base and its tip, said guiding surfaces facing towards and running in a straight line substantially parallel with but at a distance from the bases of the teeth.

ARTHUR CORNELLIER.
